UNITED STATES PATENT OFFICE.

EDWARD G. PARKHURST, OF HARTFORD, CONNECTICUT.

DESIGN FOR A TEMPORARY CARTRIDGE-CLIP.

SPECIFICATION forming part of Design No. 30,587, dated April 18, 1899.

Application filed February 1, 1899. Serial No. 704,188. Term of patent 14 years.

To all whom it may concern:

Be it known that I, EDWARD G. PARKHURST, a citizen of the United States of America, and a resident of Hartford, in the county of Hartford and State of Connecticut, have invented and produced a new and original Design for Temporary Cartridge-Clips, of which the following is a specification.

This invention is a design for temporary cartridge-clips of the class employed for holding and feeding a packet of cartridges to the magazines of breech-loading firearms.

Figure 1 is a rear view, and Fig. 2 a front view, of my new design for cartridge-clips. Fig. 3 is an end view, in transverse section, taken on the line 3 3 of Fig 1.

This design for cartridge-clips is generally oblong with rounded ends. Along its side edges are the inwardly-turned flanges L, (shown in Figs. 2 and 3,) forming with the body

portion K of the clip a longitudinal trough or channel for receiving the cartridge heads or rims. From its opposite ends toward the middle the rearward wall M is slit to form the oppositely-disposed locker-tongues N, each of which is substantially in the form of a Latin cross having a tapering body portion.

The leading essential feature of my design is the cross-shaped tongue outlined at each end of a channel-shaped clip by slitting the rearward wall thereof.

I claim—

The design for a temporary cartridge-clip as herein shown and described.

Signed by me, at Hartford, Connecticut, 35 this 31st day of January, 1899.

EDWARD G. PARKHURST.
